S. B. McHENRY.
MOP.
FILED FEB. 20, 1922.

W. May. Durall.

BY *Victor J. Evans*
ATTORNEY

WITNESS:

UNITED STATES PATENT OFFICE.

SAMUEL B. McHENRY, OF BLOOMSBURG, PENNSYLVANIA.

MOP.

Application filed February 20, 1922. Serial No. 538,029.

To all whom it may concern:

Be it known that I, SAMUEL B. McHENRY, a citizen of the United States, residing at Bloomsburg, in the county of Columbia and

5 State of Pennsylvania, have invented new and useful Improvements in Mops, of which the following is a specification.

This invention relates to clamps and has particular application to a clamp designed 10 to associate a mop head with the handle of the mop.

One of the chief characteristics of the invention resides in the provision of a two part clamp, the component parts of which 15 can be quickly and conveniently separated from either the mop head, handle or both, as the case may require.

Another object of the invention resides in providing a clamp of the above mentioned 20 character, designed to permit the mop head to rest perfectly flat upon the floor or surface, thereby covering the maximum area, and allowing the pressure to be equally distributed over the mop.

25 A further object of the invention consists in defining the component parts of the clamp for interfitting association, to prevent a relative movement of said parts, or relative movement of the mop head with 30 respect to the clamp when the parts are arranged for use.

In carrying out the invention I provide each part of the clamp with reinforcing ribs 35 which are discretionately arranged to afford the clamp in its entirety maximum strength and rigidity.

The nature and advantages of the invention will be better understood when the 40 following detail description is read in connection with the accompanying drawing, the invention residing in the construction, combination and arrangement of parts, as claimed.

In the drawing, forming part of the application, like numerals of references indicate similar parts in the several views, and wherein:—

Figure 1 is a side elevation of a mop illustrating the clamp forming the subject matter of the present invention.

Figure 2 is a top plan view of the clamp.

Figure 3 is a bottom plan view.

Figure 4 is a sectional view taken on line 4—4 of Figure 1.

55 Figure 5 is a fragmentary sectional view of a modification.

Referring to the drawing in detail, A indicates a mop head which is supported upon the handle B, through the instrumentality of the clamp forming the subject matter of the present invention. The mop head is of well known construction and includes an endless frame, the opposed sides of which are herein indicated at 10 and 11, respectively. 60

The clamp above referred to consists of two parts, indicated at 12 and 13, respectively, and each part includes a semi-cylindrical portion 14 to partly embrace the handle B, and an offset obliquely disposed portion 15. The part 12 of the clamp is formed to provide the central longitudinally disposed rib 16 which serves to reinforce and strengthen this part, and it will be noted that this rib extends across the angle defined by the respective portions 14 and 15. The portion 15 terminates to provide an offset curved extremity 17, for a purpose to be hereinafter described. 70

The portion 15 of part 13 of the clamp terminates to provide an offset curved extremity being curved in an opposite direction as compared with the extremity 17 of the part 12, which it is adapted to receive, incident to the association of the respective 75 parts of the clamp in a manner illustrated in Figure 1. These curved extremities not only serve to interlock the respective parts of the clamp together, but they unitedly define a loop, which receives the side 10 of the 80 mop frame. The opposed side 11 of this frame is received by a transversely disposed recess or depression 19 formed in the part 13 of the clamp, and held therein by means of the part 12 of the clamp. Formed on 85 the under side of this depressed portion 19 are spaced ribs 20 which strengthen this particular point of the clamp as will be readily understood. The portion 15 of the part 13 of the clamp is formed with a longitudinally disposed rib 21 arranged between the curved extremity 18 thereof and the depressed portion 19. This rib 21 in 90 addition to adding considerable strength to the clamp is disposed to be positioned between the sides 10 and 11 of the frame of the mop and to also be received by the rib 16 of the part 12. Consequently when the 95 parts of the clamp are associated for use

100 as illustrated in Figure 1, this rib 21 assists in preventing lateral movement relative of either of the respective parts of the clamp, 105

110

and is also instrumental in holding the mop head in proper position for use. It is of course obvious that the semicylindrical portions 14 of the clamp are held fixed to the handle B by means of a bolt 22 which passes through all of these parts and has associated therewith a thumb nut 23. The under side of the portion 15 of the part 12 of the clamp is also provided with a rib 24 so as to properly strengthen this particular portion of the clamp. The construction and arrangement of the parts is such that the mop can be arranged flat upon the floor or surface, thereby utilizing the entire area of the mop for the purpose intended, and at the same time, making it possible to equally distribute pressure over the entire area of the mop. It will be further noted that the handle can be separated from the clamp without separating the mop head therefrom or that the handle and mop head can be both conveniently separated from the clamp as the occasion may require.

In Figure 5 I have illustrated a modified form of the invention, which differs very slightly from the preferred embodiment, and consists mainly in the use of a clamping bolt and nut 26 and 27, respectively, to hold the free ends of the clamp effectively associated, which is more or less necessary when the clamp is used with comparatively heavy mop heads. The respective parts of the clamp, as shown in this figure are indicated at 28 and 29, respectively, and are of the same general configuration as those parts hereinabove described. The section 29 is formed with the rib 30 for the reception of the rib 31 arranged longitudinally of the section 28 which receives the rib 30 in the same manner and for the purpose hereinabove described, in connection with the preferred form of the invention. The bolt 26 is passed through these ribs and has the nut 27 associated therewith, as shown. Otherwise the invention is just the same as the preferred form of the invention.

While it is believed from the foregoing description, that the nature and advantages of the invention will be readily apparent, I desire to have it understood that I do not limit myself to what is herein shown and described and that such changes may be resorted to when desired as fall within the scope of what is claimed.

What I claim is:—

1. The combination with a mop head and handle therefor, said mop head including a frame having opposed sides, of a clamp associating the head with the handle, said clamp consisting of two parts, each of which includes a portion designed to partly embrace the handle and an offset obliquely disposed portion, means formed on the obliquely disposed portions of the respective parts of the clamp for interlocking the latter, and

for clamping the opposed sides of the said frame therebetween, and means for securing the parts of said clamp to the handle.

2. The combination with a mop head having a frame including opposed sides, and a handle therefor, of a clamp associating the mop head with the handle, said clamp consisting of two parts, each having a portion designed to partly embrace the handle and an offset obliquely disposed portion, means for securing said parts of the clamp to the handle, there being oppositely curved extremities formed on said obliquely disposed portions and associated to unitedly define a loop, for the reception of one side of the said frame and one of said portions having a transverse recess or depression for the reception of the other side of the frame, whereby said frame is clamped between said portions.

3. The combination with a mop head including a frame having opposed sides and a handle therefor, of a clamp associating the said head with the handle, said clamp consisting of two parts, each including a portion designed to partly embrace the handle and an offset obliquely disposed portion, means for securing the clamp to the handle, there being oppositely curved extremities formed by the obliquely disposed portions and arranged for interfitting association to hold said parts of the clamp together, and unitedly defining a loop for the reception of one side of the frame, one of said obliquely disposed portions having a transverse recess for the reception of the other side of the frame, whereby said frame is clamped between said portions, reinforcing ribs formed on the said oblique portions of the respective parts of the clamp, certain of said ribs being arranged for interfitting association for the purpose specified.

4. A two part clamp of the character described, each part including a semi-cylindrical portion and an offset obliquely disposed portion, there being oppositely curved extremities formed on the obliquely disposed portions for interfitting association, and unitedly defining a loop, a longitudinally disposed reinforcing rib formed on one part of the clamp and extending over the obliquely disposed portion thereof, a corresponding portion of the other part of the clamp having a transversely disposed recess, reinforcing ribs on the last mentioned portion and one of said ribs being arranged between the curved extremity and said recess arranged to be received by the first mentioned rib of the other part of the clamp, and a fastening bolt passed through the respective parts of the clamp for the purpose specified.

In testimony whereof I affix my signature.

SAMUEL B. McHENRY.
